DESIGN FOR A COMBINATION TRAILER AND BOAT OR SIMILAR ARTICLE

Guy W. Patterson, Los Angeles, Calif.

Application March 1, 1946, Serial No. 126,992

Term of patent 7 years

(Cl. D14—3)

To all whom it may concern:

Be it known that I, Guy W. Patterson, a citizen of the United States and a resident of Los Angeles, county of Los Angeles, State of California, have invented a new, original, and ornamental Design for a Combination Trailer and Boat or Similar Article, of which the following is a specification, reference being had to the accompanying drawing, forming a part thereof.

The essential features of the design are shown in full lines.

I claim:

The ornamental design for a combination trailer and boat or similar article, as shown and described.

GUY W. PATTERSON.
